CLAIM

The ornamental design for an extension pole, as shown and described.

DESCRIPTION

FIG. 1 is a front side elevation view of the present design, an extension pole, in the collapsed position.

FIG. 2 is a top plan view of the extension pole, in the collapsed position, shown in FIG. 1.

FIG. 3 is a rear side perspective view of the extension pole, in the collapsed position, shown in FIG. 1.

FIG. 4 is a front side elevation view of the present design, an extension pole, in the extended position.

FIG. 5 is a top plan view of the extension pole, in the extended position, shown in FIG. 4.

FIG. 6 is a rear side perspective view of the extension pole, in the extended position, shown in FIG. 4.

FIG. 7 is a front side perspective view of a second embodiment of the extension pole, in the extended position.

FIG. 8 is a top perspective view of a second embodiment the extension pole, in the extended position.

FIG. 9 is a rear side perspective view of a second embodiment of the extension pole, in the extended position.

FIG. 10 is a perspective view of the extension pole, in the extended position, shown in FIG. 1, wherein the broken lines in the drawing depict unclaimed environmental subject matter; and,

FIG. 11 is a perspective view of the extension pole, in the extended position, shown in FIG. 7, wherein the broken lines in the drawing depict unclaimed environmental subject matter.
